UNITED STATES PATENT OFFICE.

EDWARD W. NEWELL, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

FRICITION DRAFT-GEAR.

1,255,916.

Specification of Letters Patent. Patented Feb. 12, 1918.

Application filed June 23, 1914, Serial No. 848,747. Renewed June 23, 1917. Serial No. 176,633.

To all whom it may concern:

Be it known that I, EDWARD W. NEWELL, a citizen of the United States, residing at Pittsburgh, in the county of Allegheny and 5 State of Pennsylvania, have invented new and useful Improvements in Friction Draft-Gears, of which the following is a specification.

This invention relates to friction draft gear as applied to railway cars for yielding 10 resisting draft and buffing stresses.

The principal object of my invention is to provide an improved friction draft gear of the type having the friction surfaces inclined to the line of draft in which a single set of draft springs is employed or both draft and buffing, so that the gear may be applied in a confined space.

Other objects and advantages will appear 20 in the following more detailed description of the invention.

In the accompanying drawings; Figure 1 is a vertical section of a friction draft gear embodying my invention showing the parts 25 under a buffing stress; Fig. 2 a similar view, showing the parts in normal release position; Fig. 3 a horizontal section of the above draft gear; Fig. 4 a vertical section of a portion of the friction draft gear, showing a 30 slight modification; Fig. 5 a vertical section of a modified form of friction draft gear embodying my invention, showing the parts under a buffing stress; Fig. 6 a similar view, showing the parts in normal position; 35 Fig. 7 a horizontal section of the draft gear shown in Figs. 5 and 6; and Fig. 8 a transverse section on the line *a—a* of Fig. 5.

Referring to Figs. 1, 2, and 3 of the drawings, the friction draft gear is shown 40 applied to a car having the usual car floor 1, bolster 2, and center sills 3, the draw-bar 4 being supported by a strap 5 secured to the center sills and the friction draft gear by a similar strap 6.

The friction mechanism of the draft gear 45 preferably comprises a front follower plate 7 having oppositely inclined friction faces 8, a rear follower plate 9 having oppositely inclined friction faces 10, and wedge blocks 7 having oppositely inclined friction faces 8, a rear follower plate 9 having oppositely 50 inclined friction faces 10, and wedge blocks 11 having inclined friction faces adapted to engage the friction faces of the follower plates.

Said wedge blocks also have inclined friction faces adapted to engage corresponding

friction faces on central wedge blocks 12 55 and the last mentioned wedge blocks are centrally apertured to receive a bolt 13 which extends rearwardly and carries the draft springs 14 and 15.

Said springs are positioned between a 60 front retainer 16 and an adjusting nut 17, the spring retainer 16 preferably having a concaved outer face adapted to engage a similar face of the rear central wedge block 12, so that draft spring mechanism can adjust 65 itself to irregularities of construction or movement.

According to the construction shown in Figs. 1, 2, and 3, the rear follower 9 is connected to the draw-bar 4 by links 18 having 70 enlarged ends 19 and adapted to extend through slots provided in the rear follower.

The front ends of the links 18 are provided with slots 20 to receive a key 21 carried by the draw-bar 4. Plates 22 are secured to the center sills 3 and are provided with stops 23 for the front follower 7 and 75 stops 24 for the rear follower 9.

When the parts are assembled, the nut 17 may be screwed up so as to place the 80 draft springs 14 and 15 under the desired initial compression and in position, one of the flat sides of the nut 17 is arranged to rest on a strap 25 secured to the center sills, so as to prevent rotation of the nut 85 on the rod 13.

In operation, if a buffing stress is applied to the draw-bar 4, the inward movement of the draw-bar operates to move the front follower 7 in the same direction, and the 90 rear follower 9 being held stationary in this direction by engagement with the stops 24, the wedge blocks 11 are forced rearwardly and inwardly against the frictional resistance between same and the central wedge 95 blocks and the follower plates. In this movement, since the rear follower plate does not move, the rear central wedge block 12 will be forced rearwardly, compressing the draft springs 14 and 15, as shown in Fig. 100 1 of the drawings.

In draft, the action is similar, except that the draft stress is transmitted from the draw-bar 4, through the links 18 to the rear follower 9 and as the front follower is now 105 held stationary by engagement with the stops 23, the forward movement of the rear follower operates to force the wedge blocks

11 forwardly and inwardly. This movement causes the front central wedge block 12 to be displaced toward the front and consequently the draft springs 14 and 15 are compressed by the forward movement of the bolt 13.

It will now be seen that in this construction the same draft springs are employed both for draft and buffing in connection 10 with a draft gear having its frictional resistance set up on surfaces at an angle to the line of draft.

With this construction, the draft springs are exposed so that the same may be inspected with facility and in case of breakage the springs may be replaced without removing the gear from the car.

According to the draft gear construction shown in Figs. 5 to 8 of the drawings, means 20 are provided for facilitating the release consisting of an additional spring adapted to act between the draw-bar and the friction mechanism, so that after a buffing or a draft stress, the spring will be effective to assist 25 the release by the direct action thereof.

The draft gear shown is similar to that illustrated in Figs. 1, 2, and 3 of the drawings, but the front follower 7' is made deeper to provide a cavity 26 for the reception of a release spring 27 adapted to act between the front central wedge block 12" and the front wall of the follower 7'. The links 18' are also somewhat different 30 from those shown in the previous figures, being provided with slotted rear ends for receiving vertical keys 28. The rear follower 9' is provided with side extensions 29, having slotted projections at the top and bottom for the keys 28, so that the 35 links 18' may be connected to said follower, by means of the keys, the end of the link being inserted in the pocket formed between said projections.

The operation of this draft gear under 45 buffing and draft stresses is the same as that of the construction shown in Figs. 1, 2, and 3 of the drawings, as will be evident, but in releasing after a buffing or draft stress has been applied, the release 50 spring 27 being under compression at this time, the force of said spring acts to assist the return movement of the draw-bar to normal position. It may also be noted that the force of the spring 27 is effective 55 to increase the resistance of the draft gear in opposing draft and buffing stresses.

If it is desired to provide a draft gear having less capacity in draft than in buffing, the construction may be modified as 60 shown in Fig. 4 of the drawings.

In this case either the construction shown in Figs. 1, 2, and 3 or the form shown in Figs. 5 to 8 may be employed, the modification consisting in providing 65 radial projections on the spring retainer

16" adapted to engage the stops 24". By this arrangement, the force of the draft springs is prevented from acting on the rear central wedge block when a draft stress is applied, so that the frictional resistance is limited to that set up by the engagement of the rear follower and the front central wedge block with the intermediate wedge blocks. In buffing, however, the same action is obtained as with 75 the previously described constructions.

Having now described my invention, what I claim as new and desire to secure by Letters Patent is:

1. In a friction draft gear, the combination with laterally movable friction blocks having inclined friction faces, of longitudinally movable central wedge blocks having friction faces adapted to engage the friction faces of the friction blocks, 80 means operating under buffing and draft stresses for moving the friction blocks laterally inward to thereby spread the wedge blocks apart, a spring acting on one wedge block and a rod extending through both 85 wedge blocks for transmitting the action of the spring to the other wedge block.

2. In a friction draft gear, the combination with front and rear followers having inclined friction faces, opposed central 95 wedge blocks having inclined friction faces, and wedge blocks having friction faces for engaging the friction faces of the followers and the central wedge blocks, of a single set of draft springs for opposing movement of the friction members under both 100 draft and buffing stresses.

3. In a friction draft gear, the combination with front and rear followers having opposed oppositely inclined friction faces, 105 opposed central wedge blocks having oppositely inclined friction faces, and intermediate wedge blocks having friction faces for engaging the friction faces of the followers and the central wedge blocks, of draft 110 springs located in the line of draft at one side of the friction members and a bolt for operatively connecting the springs to the friction members for opposing the movement of the friction members under both 115 draft and buffing stresses.

4. In a friction draft gear, the combination with a draw-bar and friction members having the friction faces thereof inclined to the line of draft, of a draft spring in the 120 line of draft for opposing movement of the friction members under buffing and draft stresses applied to the draw-bar and a release spring interposed between the friction members and the draw-bar.

5. In a draft gear, in combination, a pair of opposed followers, two sets of friction elements interposed between the followers, a spring back of the rearward follower and located on the axis of the gear, abutments 130

between which the spring reacts, and connection between each abutment and one of the sets of friction elements.

6. In a draft gear, in combination, two sets of friction elements, a spring in line therewith and with the axis of the gear, abutments between which the spring reacts, a tension element connecting one of the abutments with one of the sets of friction elements, and a thrust element connecting the other abutment with the other set of friction elements.

7. In a draft rigging, in combination, a spring on the axis of the gear, two abutments between which the spring reacts, two sets of friction elements forward of the spring and connected, respectively, with the front and rear abutments and arranged to cause the abutments to travel toward each other in both draft and buff.

8. In a draft gear, in combination, links, two sets of friction elements inclosed within the links, a spring exterior of the links and in line with the gear, said spring reacting

on the two sets of friction elements independently of the links. 25

9. In a draft gear, in combination, links, two sets of friction elements inclosed within the links, a spring back of the links, a rod extending rearwardly of the links and 30 connecting the spring with one set of friction elements, and means independent of the links connecting the spring with the other set of friction elements.

10. In a draft gear, in combination, 35 links, two sets of friction elements inclosed within the links, a spring back of the links, and a rod extending rearwardly of the links and connecting the opposite ends of the spring one with each of the sets of friction 40 elements.

In testimony whereof I have hereunto set my hand.

EDWARD W. NEWELL.
